MATERNITY GARMENT

Annabel M. Spang, Cleveland, Ohio

Application June 21, 1938, Serial No. 214,899

2 Claims. (Cl. 2—76)

This invention relates to maternity garments and more particularly to a garment comprising a skirt having a vest and a blouse connected to the top thereof and which garment will enable the wearer to use a panel-front closed skirt while enabling the size of the waistline to be varied from time to time as circumstances may require.

I accomplish this general object by the construction and arrangement of parts shown in the drawing herein wherein Fig. 1 illustrates a garment made in accordance with my invention and showing the same as worn; Fig. 2 is a large detail in section taken on the line 2—2 of Fig. 1; Fig. 3 is a perspective view showing the skirt and blouse disconnected; Fig. 4 is an elevation showing the upper portion of the skirt and the vest; and Fig. 5 is a diagrammatic sectional view showing the manner in which the vest and blouse are fastened to the top of the skirt.

Describing the parts herein by reference characters, A represents the complete skirt, B the complete blouse, and C the vest. The skirt comprises essentially a front portion and a back portion, with side portions connected thereto and adapted to be folded over and adjustably connected at their upper ends with the upper end of the front portion. The front and back members of each side portion are also connected, preferably throughout a portion only of the lengths of their upper ends, by fastening devices; and the bottom of the blouse is connected to the tops of these side portions and to the back portion in a manner to be described hereinafter.

The skirt, as shown in the drawing, comprises a plurality of front, rear, and side gores, preferably eight in number and being indicated respectively at 11, 12, 13, 14, 15, 16, 17 and 18. The outer portions of the upper ends of the side gores 12 and 13 and the outer portions of the upper ends of the side gores 16 and 17 are shown as stitched together, as indicated at 19 and 20. The tops of the gores 12 and 13 and the tops of the gores 16 and 17, between the stitched portions thereof and their junctions with the next adjacent front and rear gores are provided with fastening devices 21, which may be of the ball-and-socket type of snap-fastener construction. The top of each of the gores 11 and 18 is also provided with the members 22a of fasteners (preferably of the ball-and-socket type of snap fastener construction), the opposite members 22 whereof are carried near the outer upper corners of the gores 12 and 17. It will be noted

that, with the parts of the skirt in the positions shown in Fig. 3, the waistline comprises the combined lengths of the tops of the gores 11, 14, 15 and 18, the adjacent portions of the gores 12, 13, 16 and 17 being closed at this time by means of the fasteners 21.

The bottom of the vest C is sewed to the tops of the panels 11 and 18 and is fastened at its upper end around the neck of the wearer in any approved manner.

The blouse B is of more or less conventional shape, being provided with fastening means 23 at the neck and having an open front provided between right and left front parts 24 and 25. The front corner portion of the bottom of the part 24 is sewed to the top of the gore 13 at a point which will bring the corner preferably adjacent to about the central fastening member 22a, when the gores 12 and 13 are folded forwardly; and the bottom of the part 24 is stitched further along the top of the gore 13 to its junction with the gore 14. The bottom of the front part 25 is fastened in the same manner to the top of the gore 16; and the bottom of the back portion of the blouse is stitched to the tops of the gores 14 and 15.

With the parts constructed and arranged as described, the operation will be readily understood. With the fastening elements 22 connected to the innermost fastening elements 22a and with all of the fasteners 21 in use between the gores 12, 13 and 16, 17, the waistline of the garment is at its smallest dimension, this dimension being determined by the length of the tops of the gores 11, 14, 15 and 18. When it is desired to let out the waist, the fasteners 21 which are nearest adjacent to the gores 14 and 15, respectively, are disconnected and the fastening elements 22 are then moved outwardly and engaged with the next corresponding elements 22a. This operation can be repeated as frequently as desirable, it being noted that the number and spacing of the fastening members may be varied as desirable. During these operations, the bottoms of the fronts 24 and 25 of the blouse will move outwardly, but the space therebetween will be kept closed by the vest C during all adjustments of the waistline.

By the construction shown and described herein, it will be evident that I have produced a garment which will preserve the appearance of a panel-front closed skirt with an integral or attached blouse throughout all adjustments of the waistline, in place of the "wrap-around"

skirt which is customarily used as a maternity garment.

For convenience of description, the terms "front" and "rear" have been applied to the 5 members of the side portions (12, 13 and 16, 17) when they occupy the position shown in Fig. 3.

Having thus described my invention, what I claim is:

1. A garment comprising a skirt, a vest, and 10 an open-front blouse, the said skirt comprising a central front portion, a central back portion, and side portions comprising each a front member and a back member connected at their outer edges and constituting extensions of the 15 outer edges of the adjacent central front and back portions, respectively, the central front portion being provided adjacent to the top thereof with laterally spaced fastening members extending outwardly from and arranged on opposite 20 sides of the center thereof, the front member of each pair of side members being provided adjacent to the upper outer corner thereof with a fastening member adapted to cooperate with the fastening members on the side of the front 25 central portion adjacent thereto, and laterally spaced fastening members detachably connecting the upper ends of the front and back members of each side portion, the last-mentioned fastening members extending laterally outwardly 30 from points closely adjacent to the upper ends of the central front and back portions from which said side portions respectively extend, the vest comprising a front portion secured to the top of the central front portion of the skirt, and 35 the blouse having front and back parts, the bottom corner portion of each of said front parts being secured to the top of the rear member of the side portion therebelow at a point remote from the inner edge of said member and the 40 bottom of the back of said blouse being secured to the top of the central back portion of the

skirt, the lower portion of the vest being of such width and the fastening members being so located that the lower portion of the vest will be overlapped by the lower front portions of the blouse in all positions to which the top of the 5 skirt may be adjusted.

2. A garment comprising a skirt, a vest and an open-front blouse, the skirt comprising a centrally arranged pair of front gores, a centrally-arranged pair of back gores and pairs of 10 front and back side gores, each of the first-mentioned front gores being provided adjacent to the top thereof with laterally spaced fastening members and the front gore of each pair of side gores being provided adjacent to the upper outer corner 15 thereof with a fastening member adapted to cooperate with the fastening members on the adjacent central front gore when the pairs of side gores are folded in front of their respective centrally arranged front gores, and laterally 20 spaced fastening members detachably connecting the upper ends of the front and back gores of each pair of side gores, the last-mentioned fastening members extending laterally outwardly from points closely adjacent to the upper ends 25 of the centrally arranged front and back gores, the vest comprising a front portion secured to the tops of the front gores, and the blouse having front and back parts, the bottom corner portion of each of said front parts being secured to the top of the rear side gore therebelow between the inner and outer edges thereof and the bottom of the back of said blouse being secured to the tops of the centrally arranged pair 30 of back gores, the lower portion of the vest being of such width and the fastening members being so located that the lower portion of the vest will be overlapped by the lower front portion of the blouse in all positions to which the top of the 35 skirt may be adjusted.
